(57) **CLAIM**

I claim the ornamental design for set of front fork tire widening spacers, as shown and described.

DESCRIPTION

FIG. 1 is a front view of set of front fork tire widening spacers showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a rear isometric view thereof; and,

FIG. 8 is a front isometric view thereof.

The broken lines of FIGS. 1-8 are included for the purpose of illustrating portions of the device that form no part of the claimed design.

1 Claim, 8 Drawing Sheets
